ABSTRACT OF THE DISCLOSURE

A foldable receptacle and blank therefor are provided wherein at least one surface of the receptacle has a shadow box configuration. Portions of the receptacle delimiting the shadow box configuration are in self-interlocking relation and do not rely upon an accommodated product to retain said interlocking relation.

Background of the invention

Various receptacles embodying a shadow box feature have heretofore been proposed; however, because of certain design characteristics they have been beset with one or more of the following shortcomings: (a) the receptacle is of complex and costly construction; (b) it relies upon the accommodated product to retain the shadow box configuration; (c) it is awkward and difficult to set up; and (d) it fails to provide adequate protection for the accommodated product.

Summary of the invention

Thus, it is an object of this invention to provide a receptacle of the type described which avoids the aforementioned shortcomings of the prior structures.

It is a further object of this invention to provide a receptacle which is attractive in appearance, is rigid, yet inexpensive, in construction, and is capable of being readily set up either manually or with automatic equipment.

It is a still further object of this invention to provide a blank for the improved receptacle which is of simple configuration and involves only a minimum of material waste.

It is a still further object of this invention to provide a receptacle which snugly accommodates a product in an eye-appealing manner and provides protection for said product, yet permits same to be observed from opposite sides of the receptacle.

Further and additional objects will appear from the description, accompanying drawings and appended claims.

In accordance with one embodiment of the invention a foldable receptacle is provided which has at least one surface thereof of shadow box configuration. The receptacle includes a plurality of opposed wall panels which are foldably interconnected and have the corresponding inner edges thereof delimiting said one surface. Foldably connected to the surface-forming edges of first opposed wall panels are first flaps which extend convergently inwardly therefrom. To the corresponding surface-forming edges of second opposed wall panels are foldably connected second flaps which likewise extend convergently inwardly therefrom. The first and second flaps interlockingly engage one another and delimit an aperture which is recessed from said one surface and through which an accommodated product can be observed. Each of the first and second flaps has foldably connected to the distal aperture-forming edge thereof an extension flap which is folded outwardly towards an adjacent wall panel and behind the first-mentioned flap to which it is connected.

2

For a more complete understanding of the invention reference should be made to the drawings wherein:

FIG. 1 is a plan view of one form of blank for the improved receptacle.

5 FIG. 2 is a plan view of the blank of FIG. 1 shown in the form of a collapsed tubular member.

FIG. 3 is a fragmentary perspective view of one end surface of the receptacle shown in a partially set-up condition.

10 FIG. 4 is similar to FIG. 3 but showing the receptacle end surface in a further state of partial set-up condition.

FIG. 5 is similar to FIG. 4 but showing the end surface of the receptacle in a fully set-up condition and producing a shadow box configuration.

FIG. 6 is a sectional view taken along line 6—6 of FIG. 5.

FIG. 7 is a fragmentary sectional view taken along line 7—7 of FIG. 5.

20 FIG. 8 is a fragmentary sectional view taken along line 8—8 of FIG. 5.

FIG. 9 is a perspective view of one form of the improved receptacle.

FIG. 10 is a fragmentary plan view of a modified form of blank.

25 Referring now to the drawings and more particularly to FIG. 5, one form of the improved receptacle 10 is shown which is provided with a shadow box configuration at opposite end surfaces thereof. A blank 11 for receptacle 10 is shown in FIG. 1 and is preferably formed of paperboard of suitable point and finish. The blank 11 includes four rectangularly-shaped wall panels 12, 13, 14 and 15 which are arranged in side-by-side relation and have the narrow sides thereof interconnected by foldlines 16, 17 and 18, see FIG. 1. Connected by foldline 20 to one of the endmost panels (panel 12 in the illustrated embodiment) is a glue flap 21 which is adapted to be bonded to the interior surface of panel 15, when the receptacle is partially set up, so as to form a collapsed tubular member 22, as seen in FIG. 2. The configuration and size of the wall panels may vary from that shown and will depend upon the type and size of the product being accommodated within the receptacle.

As aforementioned, the form of receptacle 10, shown in FIG. 9, has a like shadow box configuration or effect

45 provided at opposite end surfaces thereof, and therefore the structural details relative to only one of the end surfaces will be hereafter described. In blank 11, panels 12 and 14 are of like rectangular configuration and are

30 of greater length than panels 13 and 15, which are also of like rectangular configuration. Panels 12 and 14, it will be noted, are arranged in alternate relation with respect to panels 13 and 15 so that when the receptacle is set up, panels 13 and 15 will be opposite one another as will also be the case with panels 12 and 14.

50 Connected by foldline 23 to the elongated side edges of panels 12 and 14 are first flaps 24 and 25 which are of like configuration. The side edges 24a and 25a of the respective flaps 24 and 25 extend convergently outwardly from opposite ends of the foldline 23. The outer ends 60 of the side edges 24a and 25a terminate at a foldline 26 which defines a shortened outer or distal edge of flap 24 or 25. Foldlines 23 and 26 are substantially parallel to one another.

65 Elongated first extension flaps 27 and 28 are connected by foldlines 26 to the outer edges of flaps 24 and 25, respectively. Each flap 27 or 28 is of like construction and has an overall length which is substantially coextensive with the foldline 23 between the respective wall panel and first flap. Foldably connected to the opposite end limits of the extension flap 27 or 28 are laterally projecting tabs 70 30. The opposite end portions of each first extension flap

27 or 28 are provided with transversely extending tongue-like portions 27a or 28a. One side of each portion 27a or 28a conforms substantially to the angularity of the adjacent side edge 24a or 25a, of the flap 24 or 25 and is separated therefrom by a slit 31, see FIG. 1.

Connected by foldlines 32 to the elongated sides of wall panels 13 and 15 are second flaps 33 and 34 which are of like construction. The side edges 33a and 34a of each flap 33 or 34 are rounded or outwardly bowed and extend convergently outwardly from opposite ends of foldline 32. Foldlines 23 and 32 are axially aligned with respect to one another and cooperate to form a single foldline.

Connected by foldlines 35 to the shortened outer edges of flaps 33 and 34 are second extension flaps 36 and 37, respectively, which are of like configuration. The length of each second extension flap 36 or 37 is substantially coextensive with the foldline 35 and thus, a substantial space 38 is provided between adjacent ends of the first and second flaps 34-25 and 33-34 and the first and second extension flaps 27-28 and 36-37.

In setting up the shadow box end of the receptacle, the collapsed tubular member 22 is erected so as to form a tube as seen in FIG. 3. Extension flaps 27 and 28 are then folded about foldlines 26 so that each of them overlies the inner or concealed surface of the respective first flap 24 and 25. When the first flaps and the respective extension flaps are in such folded relation, the end portions 27a and 28a of each extension flap and the tabs 30 carried thereby project beyond the side edges 24a and 25a of the respective first flaps 24 and 25.

With the flaps 24-27 and 25-28 in such relatively folded condition, each flap 24 or 25 is then folded inwardly and angularly downwardly relative to the respective wall panel 12 or 14 so that the tabs 30 frictionally engage in face-to-face relation the interior surfaces of the wall panels 13 and 15.

Subsequent to the first flaps 24 and 25 being folded as indicated, the second extension flaps 36 and 37 are folded downwardly so as to overlie the interior or concealed surfaces of the respective second flaps 33 and 34, see FIG. 4. With the second extension flaps so disposed, the second flaps 33 and 34 are folded inwardly towards one another and then angularly downwardly until the side edges 33a and 34a of the flaps 33 and 34 snap in behind the adjacent side edges 24a and 25a of the flaps 24 and 25, respectively. The transversely extending portions 27a and 28a subtend the second extension flaps 36 and 37 carried by flaps 33 and 34, see FIG. 6.

Because of the inherent fight-back (resistance to folding) of the blank material, flaps 33 and 34 will resiliently engage the side edges of flaps 24 and 25. In addition, the end portions 27a and 28a of the flaps 27 and 28 snugly engage the underside of folded flaps 36 and 37. Thus, an effective inter-locking of the flaps forming the shadow box end configuration is attained.

Once the one end is formed, the product to be accommodated is then placed into the receptacle from the other end so that it engages the folded extension flaps 27, 28, 36 and 37. It will be noted in FIG. 5 that the foldlines 26 and 35 cooperate to delimit an opening of reduced dimensions whereby exposure of the accommodated product is obtained.

Once the product has been positioned against the first formed end, the opposite end of the receptacle is either likewise formed into a shadow box configuration or the end is closed by folding into overlapping relation in a conventional manner the end closure flaps 38, 40, 41 and 42 as provided on the modified blank 43, shown in FIG. 10. Where a second shadow box end configuration is formed, when utilizing blank 11, the accommodated product, not shown, is readily observable from both front and rear. In instances where the accommodated product is transparent or partially transparent, the receptacle 10 permits light rays to pass therethrough and thus, presents an eye-catching and appealing package.

The dimensions of the various wall panels and flaps may be varied from that shown so as to more effectively accommodate a particular product. The extent to which the reduced opening for observing the product is recessed from the end of the receptacle may also be varied so as to present the accommodated product in its most advantageous condition.

Where the accommodated product is a tube, bottle or the like, the foldline 35 connecting flaps 33 and 36 and/or 34 and 37 may be provided with cut-outs of suitable shape C (shown in dotted lines in FIG. 10). A portion of each cut-out would extend into both of the foldably connected flaps.

Thus, a simple yet sturdy folding receptacle has been provided which may be readily folded either manually or by automatic equipment, or may assume a collapsed condition when not in use. The improved receptacle does not rely upon the accommodated product to retain the end flaps in interlocking relation.

I claim:

1. A blank of foldable sheet material for use in forming a tubular member having a shadow box configuration on at least one end thereof, said blank comprising two pairs of wall panels, the panels of said pairs being alternately arranged and foldably interconnected in side-by-side relation; first flaps having inner edges thereof foldably connected to end-forming edges of a first pair of wall panels, side edges of each first flap extending convergently outwardly from the wall panel to which it is connected and terminating in a shortened outer edge; a first extension flap foldably connected to the shortened outer edge of each first flap, said extension flap having a lateral dimension substantially coextensive with the edge of the wall panel to which said first flap is connected; laterally extending tabs foldably connected to opposite ends of each first extension flap; second flaps having inner edges foldably connected to the corresponding end-forming edges of the second pair of wall panels, each second flap having the sides thereof extending convergently outwardly from the wall panel to which it is connected and terminating in a shortened outer edge; a second extension flap foldably connected to the shortened outer edge of said second flap; said first flaps and the extension flaps and tabs connected thereto having the corresponding ends thereof spaced endwise from the adjacent corresponding ends of said second flap and the extension flap connected thereto.

2. The blank of claim 1 including a second set of like first flaps with like first extension flaps and tabs connected thereto foldably connected to the edges of said first pair of wall panels defining the opposite end of said tubular member; and a second set of like second flaps with like second extension flaps connected thereto foldably connected to the edges of said second pair of wall panels defining said opposite end of said tubular member.

3. The blank of claim 1 including a manufacturer's glue flap foldably connected to a side edge of one of the end-most wall panels.

4. The blank of claim 1 including end closure flaps foldably connected to the edges of the wall panels defining the opposite end of said tubular member.

5. The blank of claim 1 wherein the inner edges of said first and second flaps are substantially coextensive with the edges of the wall panels to which they are foldably connected.

6. The blank of claim 1 wherein each first extension flap has end portions which extend longitudinally from opposite ends of the folding connection between said first flap and said first extension flap, each of said end portions having a transverse projection extending inwardly along but separated from the adjacent convergent side edge of said first flap.

7. A folding receptacle having at least one end thereof provided with a shadow box configuration, said receptacle comprising foldably connected opposed wall panels hav-

ing the corresponding edges thereof delimiting said one end; first flaps foldably connected to the end-forming edges of first opposed wall panels, said first flaps extending convergently inwardly towards one another whereby the corresponding outer edge of each first flap is recessed from the edges of said wall panels delimiting said receptacle one end; first extension flaps foldably connected to the outer edges of said first flaps, each first extension flap being folded outwardly towards the adjacent first wall panel, each first extension flap spanning the distance between second opposed wall panels, the ends of each first extension flap being in frictional engagement with the interior surfaces of second opposed wall panels, second flaps foldably connected to the end-forming edges of said second opposed wall panels, said second flaps extending convergently inwardly towards one another whereby the corresponding outer edge of each second flap is recessed from the edges of said wall panels delimiting said receptacle one end; second extension flaps foldably connected to the outer edges of said second flaps, each second extension flap being folded outwardly towards the adjacent second wall panel; the side edges of

each second flap being lockingly engaged behind the side edges of the adjacent first flaps, and end portions of said second extension flaps being subtended by said first extension flaps.

5. The receptacle of claim 7 wherein the end thereof opposite said shadow box configured end is formed by a plurality of closure flaps disposed in overlapping relation, said closure flaps being foldably connected to said wall panels.

10. The receptacle of claim 7 wherein the end thereof opposite said shadow box configured end is of a shadow box configuration of like construction.
